UNITED STATES PATENT OFFICE.

GEORGES GUERIN, OF PARIS, FRANCE.

DESIGN FOR A BOTTLE.

Application filed May 20, 1926. Serial No. 17,777. Term of patent 7 years.

To all whom it may concern:

Be it known that I, GEORGES GUERIN, a citizen of the Republic of France, residing in the city of Paris, Republic of France, have invented a new, original, and ornamental Design for a Bottle, of which the following is a specification, reference being had to the accompanying drawing, forming a part thereof.

In the drawing:—

Figure 1 is an elevational view of one side of my bottle,

Figure 2 is an end elevational view, Figure 3 is an elevational view of the other side of my bottle, Figure 4 is a top view, and Figure 5 is a bottom view thereof.

I claim:

The ornamental design for a bottle substantially as shown.

GEORGES GUERIN.
